UNITED STATES PATENT OFFICE.

HOWARD M. BELLOW'S, OF COLUMBUS, OHIO, ASSIGNOR TO FREDERICK H. AULD,
TRUSTEE, OF COLUMBUS, OHIO.

DEVICE FOR SECURING NAME-PLATES AND THE LIKE.

1,314,731.

Specification of Letters Patent.

Patented Sept. 2, 1919.

Application filed January 2, 1917. Serial No. 140,048.

To all whom it may concern:

Be it known that I, HOWARD M. BELLOW'S, a citizen of the United States, residing at Columbus, in the county of Franklin and 5 State of Ohio, have invented a certain new and useful Improvement in Devices for Securing Name-Plates and the like, of which the following is a specification.

This invention relates to the type of name 10 plate in which the securing device is on the back of the name plate and the name plate secured in position by forcing the securing device into a hole or socket by pressure on the front of the name plate.

15 The object of the present invention is to provide a strong securing means also adapted, when the article is painted or lacquered to prepare the seat of engagement of the securing means.

20 The invention is embodied in the construction herein shown and described and then finally claimed.

In the accompanying drawing—

Figure 1 is a central sectional view 25 through a wall having a hole and a name plate and its securing member, the name plate and its securing member being shown as resting over the hole in position to be pressed into its final place.

30 Fig. 2 is a similar view showing the name plate pressed into secured position.

Fig. 3 is a plan view of the device looking at the lower side of Fig. 2.

Fig. 4 is a section like Fig. 2 of a modification.

In the views 5 designates the wall which may be that of an automobile radiator, piece of furniture or any article to which it is desired to secure a name plate. The wall 40 is made with a suitable hole as seen at 6.

7 designates the name plate which is shown to be of a diameter larger than the hole so as to cover the same.

The securing member consists of a ring 45 or plate of sheet metal annularly bent as shown and secured at its inner portion by soldering or otherwise to the rear or lower side of the name plate. The securing member is formed by annularly bending it so as 50 to form two zones 10 and 11 standing at an angle to each other with the concave side of

the ring facing the name plate. The diameter of the securing ring is made less than that of the name plate but normally of slightly larger diameter than the hole it is 55 to occupy. The inner zone 10 is deeply corrugated or ribbed so as to stiffen it. The outer zone 11 is also corrugated so that it is stiffened in its body portion. The rim of the zone 11 is thus also made wavy or jagged 60 and takes a firm hold on the seat it is to engage. Such a corrugated, jagged or waved edge also serves to break up paint, lacquer or enamel that might be adhering to the wall of the opening to be engaged by said 65 edge. The inner zone 10 is the narrower one and more nearly approaches or coincides with the direction of the axis of the securing member than the outer zone 11. The inner zone is therefore quite stiff and offers great 70 resistance to stress applied to the outer zone. The outer zone by reason of its width and angular relation to the other zone and name plate is sufficiently yielding under pressure applied to the name plate to enter the hole. 75 6 provided for it as illustrated in Figs. 1, 2 and 3. When pressed into position as shown in Fig. 2 the outer edge of the securing member grips the walls forming the hole with great tenacity, even if the wall be of 80 metal and the hole of the ordinary boring or punching. My experience has been that when properly made the name plate can only be removed by a virtual destruction of the 85 securing member.

In Fig. 4 a countersink in the wall is provided to receive the name plate. In such a construction the name plate will be still more difficult to remove because a prying instrument can not be conveniently pressed 90 under its rim.

What I claim is:

The combination with a name plate of means for securing the same to an orifice consisting of a resilient radially-corrugated, 95 ring-like member secured to the name plate and inclined toward the same, said ring-like member being of slightly greater diameter than the orifice to be engaged and adapted to be circumferentially sprung into rim engagement therewith.

HOWARD M. BELLOW'S.
